PILOT'S SHOULDER SAFETY BELT TAKE-UP
REEL ASSEMBLY

John C. Beirise, Dayton, Ohio

Application June 27, 1940, Serial No. 342,748

2 Claims. (Cl. 242—107)

(Granted under the act of March 3, 1883, as
amended April 30, 1928; 370 O. G. 757)

The invention described herein may be manufactured and used by or for the Government for governmental purposes, without the payment to me of any royalty thereon.

The present invention relates to a reel, and has particular reference to a spring-operated take-up reel for use in connection with a safety belt, or harness, in an airplane or the like.

In performing the many functions attending the operation of an airplane or the like, it is often desirable to obtain momentarily an increased freedom of bodily movement beyond that allowed by the safety belt. This is particularly true where body movement is greatly restricted by a shoulder belt which prevents the wearer from leaning forward. In such cases it is desired to obtain this increased freedom without uncoupling the safety belt release, and it is further desired that the original condition and tension of the belt may be restored instantly as soon as the temporary looseness is no longer desired.

The object in general, therefore, of the invention is to provide an improved adjustable securing means for a safety belt, which will provide slack when needed without disengaging the belt, and which will quickly take up the slack and lock the belt at the desired tension for normal use.

A further object is to provide an improved securing means of the type described, which will function with speed and certainty without careful attention on the part of the user.

A particular object is to provide a novel spring-operated take-up reel having locking means conveniently manipulable for temporary manual release.

In the drawings, wherein for the purpose of illustration is shown only a preferred embodiment of the invention:

Figure 1 is a side elevation view of a chair in an airplane or the like, having the reel of the present invention attached thereto;

Figure 2 is a fragmentary front elevation view corresponding to the lower part of Figure 1;

Figure 3 is a side elevation of the reel with certain parts broken away;

Figure 4 is a section on the line 4—4 of Figure 3;

Figure 5 is a perspective view of the drum and cable; and

Figure 6 is a fragmentary sectional view showing the manner of attachment of the cable to the drum.

In Figures 1 and 2, the reel, indicated generally by the numeral 1, is illustrated as attached to the under side of a chair 2, shown in broken

lines. Chair 2 carries means of attachment 3 and 4 for the safety belt, either means 3 or means 4, or both, being capable of use with different types of belt. In the present instance only a fragmentary portion 5 of a safety belt is illustrated, the lower end of which may be attached directly to the attaching means 3 or to a lap belt secured to the attaching means 4.

The reel 1 is mounted within a housing 10 of generally cylindrical shape and having a bracket 11 thereon for attachment to a chair or other support. The housing 10 is closed at its ends by the end plates 12 and 13, respectively, which carry a central shaft, or spindle, 14. The end plate 13 is shown in Figure 3 as being formed integrally with the housing 10, but if desired this end plate may be formed separately and attached to the housing as is done in the case of the end plate 12. Shaft 14 is secured at its ends to the end plates 12 and 13 by means of pins or the like 15. The other end of the shaft 14 is bifurcated and contains a pin 16 therein for purposes presently to be described. In the present instance the shaft 14 has an end portion 17 of lesser diameter than the main bearing portion 18 which extends through the end plate 13. Rotatively mounted upon the shaft 14 is the drum 20 having one end recessed as shown at 21 to house a spring 22. The spring 22 has its inner end secured to the slender portion 17 of the shaft 14 and its outer end secured to the inner wall of the recess 21. In the present embodiment, the recess 21 extends substantially half the length of the drum 20, the spring 22 being of a width substantially equal to the depth of this recess. The length of the slender portion 17 of the shaft, inwardly of the end plate 12, also corresponds approximately to the depth of the recess 21. The other end of the drum 20 is externally recessed to provide a cable-winding portion 23 of slightly reduced diameter, so as to leave flanges or shoulders 24 and 25 to guide the cable. The housing 10 is provided with an opening 26 which may be designed as a further guide means for the cable.

A plurality of holes 30 and 31 are drilled in the end of the drum 20 and extend within the cable-winding portion 23 in the manner illustrated. The holes 30 are drilled uniformly to the depth shown in Figure 3, thereby reducing the weight of the device, and are, in the present embodiment, seven in number. The hole 31 is similar to the holes 30, except that it extends almost into the recess 21, so as to underlie the entire length of the cable-winding portion 23. An opening 32, drilled through the cylindrical sur-

face of the cable-winding portion 23, communicates with the inner end of the hole 31, so that an end of a cable 33 may be passed through the opening 32 and into the hole 31, where it may be frayed out and secured by solder or the like 10 34. The other end of the cable 33 is provided with an eye splice 34. The solder or other securing means in the hole 31 is confined to the inner end of the hole so that the remaining effective depth will be substantially the same as 15 the depth of the holes 30.

Mounted in the end plate 13 is a detent pin 40 adapted to selectively engage the holes 30 and 31. The pin 40 is provided with an enlarged bifurcated head 41 which limits its inward travel 15 and has pivotal connection with a lever 42 rockably carried by the pin 16 on the shaft 14. Directly beneath the lever 42 the end plate 13 is provided with an integral housing or well 43 containing a spring 44 to urge the lever 42 into a position which will force the detent pin 40 into one of the holes 30 or 31. The outer end of the housing which forms the well 43 may be bifurcated, as at 45, in the same manner as the end of the shaft 14, so as to accommodate and guide the movement of the lever 42. A suitable bearing piece transmits the thrust of the spring 44 to the lever 42. A push rod 46 having a manipulable button 47 is provided for moving the lever 42 in opposition to the spring 44, to withdraw the detent pin 40, to free the drum 20. The extent of such movement of the lever 42 is limited by the spring 44 and by the depth of the bifurcated portion 45, so that the pin 40 will not be entirely withdrawn from the end plate 13. One or more bearing brackets 48 may be attached to the chair to support the push rod 46.

In assembling the device, the portion 23 of the drum is wound full of cable, and the drum is then placed under slight tension by the spring 22 and locked in position by the pin 40. The reel may then be attached to a chair in the manner shown in Figure 1 and the eye splice 34 fastened to the end of a safety belt strap, such as 5. It is understood that in normal operation the detent pin 40 is always in engagement with one of the holes 30 or 31, so that the reel normally functions as a solid point of attachment for the end of the strap 5 on the safety belt. When it is desired to obtain additional looseness, or slack, in strap 5, the button 47 may be depressed, allowing the reel to unwind the required amount of cable against the tension of the spring 22. As long as the button 47 is depressed, the reel is free to rotate in either direction, and the tension of the spring 22 will maintain cable 33 and strap 5 taut. When the desired slack has been obtained, the button 47 may be released to lock the drum in its new position. The slack obtained in this manner will be available until the button 47 is again depressed, whereupon the spring 22 will cause the

drum to reel in all the loose cable and draw up the strap 5 snugly against the wearer. When the desired snugness of the strap is obtained, the button 47 may be released to anchor the belt in position.

Thus the reel of the present invention provides a means capable of convenient manipulation, both for adjusting the safety belt to the size of the wearer and also for obtaining an increased range of movement when it is necessary to lean forward. Once the body of the user has pulled out the necessary slack, he has freedom of movement within the range of such slack, unimpeded by the tension of the reel spring. If a sudden energy should demand that the safety belt be immediately returned to its original snugness, a mere touch upon the button 47 will cause the belt to be drawn up and locked without further attention on the part of the wearer.

Changes in the construction and arrangement of parts may be made which do not depart from the spirit and scope of the invention as defined in the appended claims.

Having now described my invention and a preferred manner in which the same may be used, what I claim as new and desire to secure by Letters Patent is:

1. In a take-up reel, a housing, a shaft carried by said housing and having an end extending therefrom, a drum mounted on said shaft within said housing, a plurality of holes in one end of said drum and arranged in a circle concentric with said shaft, a cable on said drum and having one end anchored in one of said holes, a recess in the other end of said drum, a spring in said recess for winding said cable on said drum, a detent plunger carried by said housing and engageable with said holes to lock said drum against rotation, a lever connected with said plunger and pivotally mounted on said end of said shaft, a spring in said housing acting on said lever to urge said plunger into locking engagement with said drum, and means for moving said lever against the action of said spring to withdraw said plunger to permit rotation of said drum.

2. In a reel, a housing, a shaft carried by said housing, a drum revolvably mounted on said shaft and within said housing, said drum having a plurality of holes in one end thereof arranged on a circle concentric with said shaft, a detent plunger carried by said housing and movable into said holes to lock said drum against rotation, a lever connected with said plunger and pivotally mounted on an end of said shaft, a spring mounted in said housing and acting on said lever to move said plunger into one of said holes, and means to move said lever against the action of said spring to withdraw said plunger to permit rotation of said drum.

JOHN C. BEIRISE.

CERTIFICATE OF CORRECTION.

Patent No. 2,257,099.

September 30, 1941.

JOHN C. BEIRISE.

It is hereby certified that error appears in the printed specification of the above numbered patent requiring correction as follows: Page 2, second column, line 15, for the word "energy" read --emergency--; and that the said Letters Patent should be read with this correction therein that the same may conform to the record of the case in the Patent Office.

Signed and sealed this 25th day of November, A. D. 1941.

(Seal)

Henry Van Arsdale,
Acting Commissioner of Patents.
